*Primary Examiner—Lucy LiebermanAttorney, Agent, or Firm—Fitch, Even, Tabin & Flannery[57] CLAIM

The ornamental design for a bottle, as shown and described.

DESCRIPTION

FIG. 1 is a perspective view of a bottle showing my new design;

FIG. 2 is a top plan view thereof;

FIG. 3 is a front elevational view thereof, the rear being identical thereto; and,

FIG. 4 is a side elevational view thereof, the opposite side being identical thereto.

The broken lines at the top of the bottle indicate a cap for the bottle which forms no part of the claimed design.
